FRUIT-PRESS STRUCTURE

Ben B. Manaster, Chicago, Ill.

Application May 17, 1937, Serial No. 143,050

6 Claims. (Cl. 100—42)

This invention relates to presses and more particularly to a press for the extraction of fruit juices and the like.

Among its important objects, the invention 5 contemplates the provision of a simplified structure of the class described which is relatively inexpensive to manufacture, which is rugged yet simple in construction, and which is highly efficient in use.

10 A further object is the provision of a fruit press especially constituted for manual operation for either domestic or commercial use and which includes a novel supporting structure characterized by its attractive appearance and 15 rugged supporting qualities.

A further object is the provision of a fruit press having a standard upon which is mounted an arbor comprised of two uprights of pressed sheet metal formed with a plurality of longitudinal ribs to produce a supporting member of substantially polyhedral form, the pair of uprights being surmounted by a head bar which is cast onto the supports and upon which is mounted the pressing mechanism.

20 A still further object is the provision of a fruit press comprised of a base member having mounted thereon a pair of spaced upright supports of pressed steel having a head bar secured across the upper extremities thereof by means 25 of casting, the uprights having integral intermediate formations for supportably engaging an annular platform in which is removably seated a 30 pressing cup.

Yet another object is the provision of a press 35 including a supporting structure formed of relatively simple metal stampings in the manner heretofore described, together with a supporting member cast onto the stampings and the latter being mounted on a base member by tongue and slot means providing for simplified assembly, the 40 stampings further having an arrangement of supporting areas or lugs engageable with an annular supporting ring of channel-like cross section in a manner to be particularly pointed out 45 hereinafter.

Additional objects and novel aspects of the invention reside in the particular construction and arrangement of parts to be hereinafter described in conjunction with the annexed drawing in which:

Fig. 1 is a side elevation of the improved press structure;

Fig. 2 is a vertical fragmentary section drawn to enlarged scale and taken along line 2—2 of 50 Fig. 1;

Fig. 3 is a punching of one of the upright, pressed-metal supports;

Fig. 4 is a fragmentary bottom plan view showing the method of attaching the uprights to the base as viewed in the direction of line 5—5 of Fig. 2;

Fig. 5 is a horizontal plan view along line 5—5 of Fig. 2 showing particularly the annular supporting ring or platform and the pressing cone; and

Fig. 6 is an enlarged fragmentary perspective of the mounting means for the platform ring.

In the press structures heretofore developed, the point of greatest weakness has always been the neck, arbor, or crosshead, and this will be 15 readily understood from a consideration of the fact that it is in this region that the present mechanism exerts its reaction against the stationary pressed member or cone. Likewise a point of equal weakness in these constructions 20 is the intermediate platform support. The present invention provides an inexpensive press structure which is characterized by great strength in the region of the crosshead as well as the intermediate platform support, and in ac- 25 complishing this the cost of construction of the frame has been lessened; and in addition to providing a press structure of attractive appearance and remarkable durability, the invention provides a device which is relatively cheap to 30 manufacture and which is light in weight and easily portable.

The form of the invention shown in Fig. 1 includes a base member of any suitable configuration, preferably the oblong form seen in Fig. 35 5, and has provided in its central region an annular recess 11 (see also the lower part of Fig. 2) in which a glass or like receptacle may be securely seated. The bottom of the base 10 adjacent its longitudinal or right and left hand 40 extremities is provided with inset or routed formations or recesses 12, as seen in Figs. 2 and 4, the purpose of which will appear hereafter. If desired, friction legs 13 may also be provided on the bottom of the base to prevent marring 45 and slicing.

Extended from the base 10 at points substantially overlying the bottom recessed portions 12, are a pair of oppositely disposed upright supporting arms 14 which are formed preferably 50 from metal stampings of suitable gauge or thickness, and for very rugged constructions are preferably stamped from sheet steel.

One of the punchings from which the uprights are struck or stamped is shown in Fig. 3 in the 55

form of an elongated strip of metal 15 having a substantially flared or enlarged base extremity 16 from which extend in an axial direction three evenly spaced ears or tabs 17, while the 5 opposite axial or longitudinal extremity of the punching forms a head 18 of reduced lateral width and from which extends axially a tab or ear 19 which is somewhat elongated and which has at least a pair of oppositely disposed notches 10 20 along its longitudinal edges. Between its ends, that is to say between the flared base portion 16 and the reduced head portion 18, the punching 15 has an enlarged intermediate portion 21 providing opposite wings each with opposite and peculiarly shaped ears 22 and 22' 15 formed by notching or slotting the wing portions horizontally and vertically, in the form of an L, as at 23 and 23', the ears 22 being further cut to form an angular notch 23'. The 20 ears 22 and 22' are made to provide for the subsequent formation of ring engaging or supporting means.

The punchings 15 are placed in a suitable press or stamping machine and provided with a plurality of longitudinally extensive ridges or ribs 24, and the stamping assumes a semicircular or U-shaped cross sectional form with the areas 25 between intervening ribs 24 arranged as the faces of a polyhedron, in this instance five-sided (Fig. 30 5). This operation also disposes the intermediate ring supporting tabs or ears 22 and 22' in substantially opposite relation, and the flared base portion 16 is provided with opposite legs 16'.

35 After the stampings have been formed in the manner aforesaid, the elongated tabs or areas 19 at the upper ends thereof are bent inwardly at an angle as at 26 in Fig. 2 and thereafter the stampings are inserted in pairs in a mold and are cast 40 into supporting engagement with a U-shaped cross head or bar 27. The cross head has a boss 28 in which is formed a sleeve or bore having a radial side opening (not shown) confronting the teeth 29 of a rack bar 30. A stud shaft 31 having 45 keyed thereon a pinion 32, is seated in the bore of the boss 28 for driving engagement of the pinion with the teeth 29 of the rack so that by turning the stud shaft in opposite directions the rack bar 30 may be reciprocated or moved up and 50 down relative to the base member 10, the rack bar 30 being preferably of hexagonal form and slidably in a vertical bore formed in an intermediate enlarged body portion 33 of the head bar casting 27.

55 Integrally formed with, or otherwise attached to the stud shaft 31, is a manipulating handle 34 disposed at a convenient angle so that the operator may exert a maximum leverage without undue tendency toward moving the device on its 60 support.

A pressing bell 35 of substantially frusto-conical form is attached to the rack 30 by any suitable means such as a bolt which extends into the lower axial end of the rack. In the example seen in Fig. 2, however, the reduced lower end portion 65 of the rack has been extended through an opening in the small end of the bell or cup and peened over as at 36.

Spaced uprights 14 with the cast head bar 27 70 are mounted on the base 10 by inserting the lower ears 17 into suitable slots or openings in the base and thereafter bending over the ears in the manner seen in Fig. 4.

A novel supporting platform for the pressing cone is provided in the form of a ring 37 of chan-

nel shaped cross section as indicated at 38. In mounting this platform or ring between the uprights, the rim portions 39 of the channeled bottom of the ring are fitted into the cut-away or notched portions at 23 and 23' of each of the 5 ears 22 in such manner that the latter all extend into the channel 38 of the ring, the free edge portions of the rims finding additional support in engagement with the bottoms of the slot 23' and the notch 23' of the ears 22 of the upright. If desired or necessary, the upper portions of the ears 22 may be spread or bent suitably into wedging engagement with the channeled portion 38 of the ring 37 in such manner that the latter is at all times firmly seated and supported between the 10 uprights 14 at a point between the base 10 and the cross or head bar 27 by means of the ears 22 and 22' flanking notch 23.

Removably seated in the ring or platform 37 is a round cup 40 having an annular shoulder 41 20 adjoining a reduced or narrowed bottom portion 42 which fits within the ring, the shoulder portion 41 sitting on the upper surface of the ring. The bottom 42 of this cup is open and substantially overlies the receptacle-seating recess 11 in 25 the base 10, and in addition the cup has an upstanding wall 43 of a height adequate to prevent the escape of juices or rinds therefrom during the pressing operation.

Cooperable with the pressing bell 35 is a re- 30 movable pressing cone 45 desirably formed of metal and having a plurality of spaced openings 46 distributed over its surface for the escape of juices to a receptacle positioned therebelow, these 35 openings being of a size adequate to prevent any pith or solid material from the fruit, such as seeds, from passing into the receptacle. The lower peripheral edge of the pressing cone 45 is further provided with arcuate notches or cut-away portions 47 also adapted to permit the 40 escape of the fruit juices while at the same time preventing the escape of seeds and the like.

In the operation of the device, the substance to be pressed, such for example as fruit which has been halved, is placed firmly onto the pointed 45 upper end portion of the pressing cone 45, and a glass or receptacle is seated in the recess 11 below the pressing cone and the platform 37, whereupon the operator grasps the handle 34 and turns the same to drive the rack bar 30 downwardly through 50 the action of the pinion 32 as it is revolved by manipulation of the handle. The pressing bell 35 engages the fruit, and a continued application of force to the handle 34 presses the fruit firmly down onto the pressing cone 45, causing the expulsion of the juice therein, which juice, substantially free of pith and seeds, escapes through the openings 46 and 47 and gravitates into the receptacle therebelow. The formation and angular disposition of the operating arm 34, together with 55 the gearing of the pinion and rack 30—32 is devised to give a maximum pressing force and mechanical advantage, such that the application of a relatively moderate force to the handle 34 results in a relatively great exertion of pressure between the bell 35 and the cone 45.

It is of further importance to point out that while the foregoing arrangement discloses a relatively simple construction and while the forces which are applied to the cone 45 and supporting 70 ring 37 are relatively great, yet the peculiar formation of the uprights 14 and the manner of attaching same to the cross bar 27 and the base plate 10 result in a rigid and rugged structure capable of withstanding great stresses especially 75

in the region between the ring or platform seating formations 22 and 22' and the juncture of the uppermost angularly disposed tabs or ears 19 with the cast head bar 27.

5 The foregoing particularly described arrangement of parts is illustrative of a preferred embodiment of the invention and is susceptible of rearrangement and modification without departing from the scope of the invention as defined in the 10 appended claims.

Having thus described my invention, what I claim as new and desire to protect by Letters Patent is:

1. A device of the class described including a 15 base member, a pair of spaced uprights formed of sheet metal stamped into substantially channel-shaped form with a plurality of longitudinally extensive adjacent surfaces in polyhedral array, said uprights being attached to said base member 20 by means of ear formations at their lower axial extremities extended through openings in said base member and thereafter bent over, said uprights having integral lug formations between their ends for supporting engagement with a 25 platform in the shape of a ring of channel-like cross section mounted between said uprights with the said lug formations of the latter disposed in the channel formation of the ring, pressing means mounted on said platform, a cross head cast onto 30 the upper ends of said uprights and a movable pressing device and driving mechanism therefor mounted on said cross head, said pressing device being movable toward and away from said first-mentioned pressing means on said platform by 35 operation of said driving mechanism.

2. A standard for fruit presses and the like and comprising a pair of channel-shaped sheet metal uprights mounted at their lower ends on a base member and having a crossbar cast on their upper 40 ends, said crossbar being adapted to mount pressing mechanism, and a platform structure including a supporting member having an undercut bottom and mounted between said uprights by means of opposite upright ears formed by cutting L- 45 shaped slots in opposite edge portions of said uprights, said supporting member being fitted onto said slots in each of said uprights with the said ears disposed in the cut-out portions of the supporting member.

50 3. In a device of the class described, a base member, a pair of uprights mounted on said base member, each of said uprights having a pair of aligned slot formations adapted to seat a mounting ring in cooperation with similar slots in the 55 opposite upright, said uprights being joined at their upper ends by a crosshead of rigidified moldable material cast onto said ends and having formations for mounting pressing mechanism for cooperation with pressing means supported on 60 said mounting ring.

4. A standard for a fruit press including a base, a pair of uprights secured at their lower ends to

said base and provided with fluting extended in the direction of their length, said fluting being formed by bending said uprights partially in a direction back upon themselves, each of said uprights having between their ends a pair of laterally projecting tabs in which are formed aligned mounting slots, said mounting slots being disposed when the uprights are in assembled relation to supportably receive a pressing seat, and a molded crosshead cast onto the upper ends of said uprights in a manner to attach said crosshead rigidly to the uprights, and pressing mechanism mounted on said crosshead for cooperation with pressing means mounted in said pressing seat. 5

5. A device of the class described including a 15 base and a pair of spaced sheet metal uprights of channel-shaped form with a plurality of longitudinally extending adjacent surfaces in polyhedral array, each of said uprights having integral vertically spaced pairs of ears arranged in horizontally spaced relation between the upper and lower ends thereof, a supporting member of annular shape and having an annular groove in its bottom and supported between said uprights with the lowermost ears of each of said pairs disposed 20 in the annular groove thereof and the uppermost ears of each pair overlying an upper surface portion of the supporting member to secure the same against removal, said supporting member being adapted to support a pressing member, the upper 30 end portions of said uprights being rigidly interconnected by a body of metal cast thereon and having integral cast formations constituting a mounting for pressing mechanism adapted to coact with said first-mentioned pressing member. 35

6. In a fruit press, a standard including a base, spaced uprights mounted on said base and constructed from sheet metal in an elongated strip having adjoining polyhedral surfaces extending substantially throughout its length, each of said uprights having an L-shaped slot cut into its opposite edge portions between its ends to provide upper and lower ears on each side of each upright with a slot portion between each pair of ears, means rigidly interconnecting the upper end portions of said uprights and adapted to provide a mounting for movable pressing mechanism, and an annular platform having an annular channel in its bottom supported between said uprights with a peripheral wall portion disposed in the 40 aforesaid slots in the uprights so that the lowermost ear of each pair in each upright extends into said channel in supporting engagement with the inner bottom portion of said channel, the uppermost ear of each pair in each upright being 45 turned over an upper surface portion of said platform to prevent removal of the same from said slots, said platform being adapted to support pressing means cooperable with the aforesaid movable pressing mechanism. 50

60 BEN B. MANASTER.
